UNITED STATES PATENT OFFICE.

WILLIAM F. ZIMMERMANN, OF MAPLEWOOD, NEW JERSEY, ASSIGNOR TO GOULD & EBERHARDT, OF NEWARK, NEW JERSEY, A CORPORATION OF NEW JERSEY.

CRANK-PIN LOCK NUT AND GUARD.

Application filed January 12, 1925. Serial No. 1,945.

This invention relates to shapers and it deals more particularly with means for regulating the stroke of the cutting tool.

Shapers, as commonly constructed, include a box-type column, a tool-carrying ram translatablely mounted in guideways at the top of the column and means to reciprocate the ram. One preferred means for reciprocating the ram comprises a lever of the third class, fulcrumed at one end in the lower part of the column and having its upper end pivotally connected with the ram. Power to oscillate the lever, thereby to cause reciprocation of the ram, is provided by a crank-pin carried by a bull gear and operating in a slot formed lengthwise in the lever. The bull gear is provided with a long hub journaled in the column and is adapted to be rotated continuously during the operation of the machine tool. To provide means for regulating the extent of oscillation of the lever and consequently the stroke of the ram, the crank pin is usually carried by a slide adjustably mounted in guideways provided by the bull gear and means is provided for adjusting the slide in its guideway thereby to change the eccentricity of the crank pin with respect to the axis of the gear. Inasmuch as the stroke of the ram must be changed frequently to give to the tool its required cutting stroke, the length of which is determined by the work, it is essential that the means for varying the throw of the lever (that is the means for shifting the crank-pin slide) be readily accessible to the operator and convenient of manipulation. It is also essential that means be provided to lock the slide against accidental movement after the desired setting has been effected.

This invention therefore has for its primary object to combine with the means for regulating the stroke of the ram an improved locking device for holding the parts in their adjusted positions.

A further object is to provide a locking device which may be actuated with greater facility than prior devices, which is more positive in its action, and which may be manipulated without pain or injury to the hands of the operator.

A still further object of the invention is to provide a locking device as above described, which includes a clamp nut of such shape and proportions that it readily may

be grasped by the entire hand of the operator, and rotated without his hand coming into contact with the edges thereof.

Still another object of the invention is so to construct the clamp nut that it may be utilized as a guard for the continuously rotated squared end of the lock-actuating shaft.

Another object is so to form the clamp nut that a portion thereof will serve as a stop for an actuating lever adapted to be applied to the squared end of the shaft which the nut protects.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Fig. 1 is a side elevation of a shaper embodying the present invention. Fig. 2 is an enlarged vertical section on the line $x-x$ of Fig. 1. Fig. 3 is an enlarged central section of the combined lock-nut and guard and its associated parts.

Referring more particularly to the drawings, the invention is disclosed as embodied in a shaper comprising a box-type column 1 within the upper end of which is slidably mounted the usual ram 2, carrying at its forward end a suitable tool, not shown. The ram is reciprocated by a lever 3, fulcrumed at 4, to a link 5, pivoted upon a pin 6 in the lower part of the column. Intermediate its ends, the lever is formed with a slot 7 within which is fitted a slide-block 8 carried by a crank-pin 9 adjustably mounted eccentric to the axis of a bull gear 10. Thus rotation of the bull gear, by any suitable driving mechanism, will, through the pin and slot connection 9-7 cause oscillation of the lever 3 and thereby reciprocation of the ram.

To provide means for regulating the extent of oscillation of the lever 3 and consequently the reciprocation of the ram, the crank pin is preferably so mounted on the bull gear as to be capable of radial adjust-

ment with respect to the axis of the gear. To this end the crank-pin is carried by a slide 11 adjustably mounted in ways 12 carried by the gear. A screw 13, journaled at one end in a bearing 14 provided by the gear 10, has a threaded connection with the slide 11 and acts, upon rotation of the screw, to shift the crank pin either toward or from the axis of the gear, dependent upon the direction of rotation of the screw. A pinion 15 fixed to the feed screw 13 and a bevel gear 16 secured upon a manually rotatable shaft 17, afford means to rotate the screw. The shaft 17 is journaled coaxial with the bull gear 10 in bearings 18 and 19 provided by a bearing sleeve 20. This sleeve is formed integral with the bull gear 10 and serves to journal the bull gear in a bearing boss 21 projecting horizontally from the side of the column 1. Outward movement of the bull gear and sleeve 20 is prevented by contact of the gear with the inner end 21^a of the boss 21 and a flange or plate 22, secured to the sleeve 20, by screws 23, serves to prevent inward movement thereof. The shaft 17 projects from the side of the column and is squared at 24 to receive a crank 25. This crank affords means by which the operator may rotate the shaft and, through the bevel gears 15 and 16 and feed-screw 13, adjust the slide 11 in the ways 12, to vary the eccentricity of the crank-pin 9 with respect to the axis of the bull gear, thereby to effect a predetermined stroke of the ram.

The desired setting having been effected the parts are locked in their adjusted positions to prevent accidental movement thereof. This invention provides new and improved means for effecting this locking of the parts and includes a multi-purpose member 26 threaded upon the portion 27 of the shaft 17. One of the purposes of the member 26 is to serve as a clamp-nut and therefore its end 26^a is arranged to bear against the plate 22. It will readily be perceived that inasmuch as the member 26 is held against inward movement by the plate 22, which acts as a thrust bearing, rotation of the member in one direction will cause the shaft 17 to be pulled endwise, thus drawing the gear 16 firmly against a thrust bearing 27 provided by the bull gear, thereby clamping the gear 16 against rotation. The gear being held against rotation serves to lock the pinion 15 and screw 13 and therefore the slide 11 is maintained in its adjusted positions. Reverse rotation of the member 26 releases the parts and permits the shaft 17 to be manually rotated to effect any desired adjustment of the slide.

The specific construction and arrangement of the member 26 is one of the important features of this invention. This member is preferably of cylindrical form and of a length sufficient to enable it to be

grasped by the entire hand of the operator. The outer face is preferably knurled or otherwise roughened to provide a better gripping surface for the operator's hand. This construction of the clamping nut permits the operator to grasp it tightly with his whole hand and either to tighten or loosen it with comparatively little effort and without injury or pain to his hand.

Certain types of locking devices heretofore provided have included relatively narrow locking nuts adapted to be grasped between the thumb and one or two fingers. In grasping these prior devices the operator's fingers project over the edges of the nut. Inasmuch as the gripping surface is relatively small great pressure must be applied by the fingers to tighten the nut and this pressure causes the edges of the nut to dig into the operator's fingers with more or less painful results.

The new and improved nut provided by this invention is preferably of greater width than the operator's hand and therefore in grasping the nut with his whole hand he is able to tighten the nut with less effort and also without coming into contact with the edges of the nut.

The member 26 also serves a second purpose. That is to act as a guard for the projecting square end of the shaft 17 which, during the operation of the machine-tool, is rotated continuously and is a constant source of danger to the operator. This is accomplished by having the member extend outwardly from the column as far as or further than the square end of the shaft, thus protecting both the operator and the shaft against injury. The outer end of the member 26 is counterbored at 28, thus providing clearance for the socketed end 29 of the crank 25.

A third purpose of the member 26 is to serve as a stop to limit the inward movement of the crank 25. To this end the counterbore 28 terminates in a shoulder 30 against which the inner end 29^a of the socketed end of the crank abuts thus preventing the crank from becoming jammed on the rounded portion 17^a of the shaft at the inner end of the flats 24^a forming the squared end 24.

From the foregoing it will be perceived that applicant has in a very ingenious manner and by very simple construction, provided an improved locking device for the stroke adjusting means, a guard for the stroke adjusting shaft, and a device to prevent jamming of the stroke adjusting crank.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific

aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:—

- 10 1. In a shaper, a ram; means to reciprocate the ram; means to regulate the stroke of the ram including a manually adjustable shaft; means to lock said shaft in its adjusted positions, said last named means including an elongated hand grasped clamping member threaded upon said shaft, said member being of a length substantially the width of the hand of an operator.
- 15 2. In combination with a shaper-ram stroke-regulating mechanism including an adjusting shaft having an end projecting from the side of the shaper; a hand grasped member of a length substantially the width of the hand of an operator threaded upon said shaft, said member having a portion adapted upon rotation of the member to engage a non-shiftable part of the shaper to clamp the shaft against rotation; and a portion surrounding the free end of said shaft
- 20 30 to prevent accidental contact with said shaft.
- 25 3. In combination with a shaper-ram stroke-regulating mechanism including an adjusting shaft; a member fixed to said shaft; a thrust-bearing adjacent said member and cooperating therewith to prevent endwise movement of the shaft in one direction; a second thrust bearing; an elongated hand grasped clamping element threaded upon said shaft and adapted to engage said second thrust-bearing to move said
- 35 shaft endwise thereby to draw said member into engagement with said first named thrust-bearing to lock said shaft against rotation, said clamping element being of a length substantially twice its diameter and having a roughened exterior surface.
- 40 4. In a shaper, a ram; means to reciprocate the ram; means to regulate the stroke of the ram including an actuating shaft having a threaded portion projecting outwardly from the frame of the shaper and a polygonal end projecting beyond said threaded portion and adapted to receive a crank; a cylindrical clamping nut threaded upon the threaded portion of the shaft; and a thrust bearing cooperating with said nut and

adapted upon rotation of the nut to effect endwise movement of the shaft, said nut having a sleeve-like portion surrounding said polygonal end and acting as a guard therefor, the outer surface of said nut and sleeve-like portion being continuous and forming an elongated hand-grasp of a length substantially that of the width of an operator's hand by means of which the nut may be manually rotated.

5. In combination with a shaper-ram stroke-regulating means including a stroke adjusting shaft having a free end projecting outwardly from the column of the shaper and adapted to receive an actuating crank; a guard entirely surrounding said free end of the shaft, said guard being formed with a bore adapted to admit of the insertion of a portion of the crank to engage the shaft, and an internal abutment provided by said guard to limit the inward movement of the crank.

6. In combination with a shaper-ram stroke-regulating mechanism including an adjusting shaft having a free end adapted to receive an actuating crank, a hand grasped element threaded upon said shaft and having a sleeve-like portion adapted to guard said free end of the shaft; an abutment provided by said element to limit the inward movement of the crank; a nut provided by said element to lock said shaft in adjusted positions, said parts being so constructed and arranged that the outer surface of the nut and sleeve-like portion together form a continuous hand-grasp of a length substantially that of the width of an operator's hand by means of which the nut may be rotated.

7. In a shaper, a ram; means to reciprocate the ram; means to vary the extent of reciprocation of the ram, said last named means including a manually adjustable shaft having one end projecting outwardly from the column of the shaper and squared to receive a crank; a combined shaft-clamping and shaft-guard sleeve threaded upon said shaft and extending to the free end thereof and having a bore within which the crank may be inserted and fitted upon said shaft; and an internal shoulder adapted to limit the inward movement of the crank on the squared end of said shaft.

In witness whereof, I have hereunto subscribed my name.

WILLIAM F. ZIMMERMANN.
